UNITED STATES PATENT OFFICE.

BENJAMIN¹ W. ELLICOTT, OF FLEMINGTON, NEW JERSEY.

METAL RAILROAD-TIE.

SPECIFICATION forming part of Letters Patent No. 410,684, dated September 10, 1889.

Application filed April 10, 1889. Serial No. 306,662. (No model.)

To all whom it may concern:

Be it known that I, BENJAMIN W. ELLICOTT, a citizen of the United States, residing at Flemington, in the county of Hunterdon and 5 State of New Jersey, have invented certain new and useful Improvements in Metal Railroad-Ties; and I do hereby declare the following to be a full, clear, and exact description of the invention, such as will enable others 10 skilled in the art to which it appertains to make and use the same.

My invention relates to an improved construction of metal railroad-ties adapted to be held firmly in position on a railroad-bed, trestle-work, bridge, or other structure, and serving as a substantial yet flexible rest for the 15 rails of the track.

In the accompanying drawings, Figure 1 is a perspective view of a portion of a foundation-plate, preferably made of channel-iron. 20 Fig. 2 is a vertical longitudinal section in the line x x of Figs. 4 and 5. Fig. 3 is a perspective view of one-half of the flexible rail-rest. Fig. 4 is an end view of the improved rail- 25 road-tie, showing also a side view of a portion of one of the track-rails. Fig. 5 is a top view of a portion of the said tie, showing also a portion of one of the track-rails; and Figs. 6, 7, 8, and 9 are views, in detail, of a chair- 30 plate clamping or gripping clip, inner and outer chair-plates, and a foot-abutment block.

A in the drawings is a transverse metal foundation tie-plate, preferably, but not necessarily, made of channel-iron, as shown, in 35 order to possess the requisite strength, with lightness and stiffness, for sustaining the transverse rail-rest B, which forms the track-bed. This plate A is of sufficient length, breadth, and thickness to receive the said 40 rail-rest and carry the same, as illustrated, and on the upper surface of its bottom portion are formed or applied upwardly-projecting abutment-ribs a a' a^2 a^3 , the same extending from side to side of the plate in pairs, one 45 pair beneath a right-hand track-rail C², and the other pair between a left-hand track-rail C³, as shown, and serving to prevent the rail-rest from slipping endwise or transversely of the rails C² C³, as will be presently described. 50 The ribs a a^2 are of less height than the ribs a' a^3 , and their abutting-surfaces for a portion of their depth are beveled, as at a^4 , while

below this beveled surface their abutting-surfaces and also the abutting-surfaces of the ribs a a^3 are vertical with the bottom of the 55 plate. This construction is adopted in order to facilitate the insertion of the feet c^2 c^3 of the rail-rest B by a downward pressure upon said rest, and also insure a close fit and firm 60 footing for said rail-rest.

Against the ribs a a^3 are set transverse metal abutment-blocks a^5 a^5 , said blocks being of the same length as the ribs and secured firmly in place by strong-headed screw-bolts b b , which pass up through the plate A and 65 blocks a^5 a^5 , clear of the feet c^2 c^3 , and receive nuts d^2 d^3 and also jam-nuts, if necessary, on their upper ends, as shown. These blocks have a horizontal bearing-surface and are underbeveled, as shown at c^5 c^5 , to receive 70 and hold down firmly correspondingly-beveled toes c^4 c^4 of the feet c^2 c^3 of the rail-rest B. Each block is provided with a solid lug c^8 between the beveled end portions c^5 c^5 , and the lugs of the blocks enter perpendicularly- 75 walled notches c^9 , formed in the feet c^2 c^3 of the rail-rest, and form firm stops to the same, both transversely and longitudinally of the track-rails. The outer upper surface of the abutment-blocks are preferably beveled to correspond with the top beveled surfaces of the ribs a a^3 , and inward from their top beveled 80 surfaces they are horizontal and on a level with the top surfaces of the feet of the rail-rest.

If found practicable, the ribs a a^3 and the blocks a^5 a^5 may be formed in one piece and confined by screw-bolts, or the blocks and ribs may be formed as one piece upon the 85 plate A; but the construction shown is preferable.

The rail-rest B, as shown, comprises two spliced transverse plates c c' , and, as one plate is substantially like the other, a description of plate c' will suffice as a description for the 90 plate c . Referring to Fig. 3, it will be seen that the plate c' has a foot c^2 of a thickness greater than any other portion of it and a width equal to the foundation-plate A, and that from this foot portion, at a point about one-third 95 its length from the end of the toes c^4 , a curved standard f extends upward a proper height for allowing the necessary requisite spring action to the rail-rest. In forming this stand-

ard the metal of which the rest-plate c' is formed is gradually reduced in thickness, and the top outer surface of the foot near the base of the standard f is chamfered or made 5 with a slight concavity at c^3 , and above this concavity it is bent inward on a segmental curve f' , as shown. The inner side of the standard has about the form of a semicircle, as at f^2 . From the upper portion of the 10 standard the plate c' is extended transversely and is of the same thickness of metal as the standard for about one-third its length, then is tapered along about another third, as at c^{10} , and at the termination of this last-mentioned 15 third portion of its length a flat vertical shoulder h' is formed, and from the shoulder the plate c' is extended with a lapping portion h^2 equal to about one-third its length, which has parallel horizontal surfaces, as shown.

20 By having the standard f start up from the foot c^2 at a point about one-third its length from the outer ends of the toes c^4 a great advantage is secured, for under this construction the weight of the load upon the rail-rest 25 has a tendency to keep the foot c^2 down to its foothold a^5 rather than a tendency to pry up against said foothold.

30 The plate c' has abutment-ribs $m m'$, made of different heights, so as to accommodate the 35 differently-formed chair-plates $C C'$ applied on it. These ribs are located at points forward of the curved standard f of the rail-rest in order to provide rail-chair-plate abutments, and against the outer higher abutment-rib 40 m the outer foot-flange of a rail C^2 or C^3 fits snugly and abuts, and is confined by a shouleder chair-plate C set upon the abutment-rib m , and extending down against the inner side of the said abutment-rib m and bearing upon 45 the rail, as shown, and being confined by a gripping-clip D and nuts n . The chair-plate C is longer than the width of the rest-plate c' , and the bolt ends of the gripping-clip after the clip has been passed under the rail-rest 50 can pass through the projecting ends of the chair-plate outside of the rail-rest, as shown in Figs. 4 and 5.

55 The inner foot-flange of the rail C^2 or C^3 is held down by a shouleder chair-plate C' , which abuts against the inner rib m' and against the inner edge of the rail-flange and laps over the said foot-flange of the rail, as shown. The chair-plate C' is also constructed of a greater length than the width of the rail-rest B and is confined by a gripping-clip D and nuts n , applied in the same manner as the clip of the chair-plate C .

60 The rest-plates c and c' , which differ from one another in only having the shoulder h' of the one on top and the shoulder h' of the other at the bottom, after being set and confined in the footholds of the foundation tie-plate A , as described and shown, are bolted together at their lapped ends h^2 by bolts h^4 , and when thus bolted together abut against each other at their shoulders h' , while the feet of the rail-rest abut against the abutment-

blocks a^5 , thus forming a substantial rail-rest, which is flexible between the rails and possesses in itself all the properties of a relief-spring which is capable of yielding, crosswise of the road-bed, to the great strain thrown upon it by reason of the heavy loads and the vibratory or changing motions of the train passing over the rails.

70 The flexible metal tie constructed in accordance with my invention is very enduring, readily and cheaply made, and answers a better purpose than those constructions which require auxiliary cushion-springs, 80 either of metal or rubber, as it serves both as a strong support and stay, and is capable of yielding in a curve line along its whole length between its standards $f f$ without becoming injuriously impaired in its functions after 85 short use.

90 In Fig. 2, at E , an angular knee or brace is represented bolted to the bottom plate A and abutting against a rail C^2 or C^3 under its cap. This brace may be applied at points of a rail-road bed or track where curves or elevations and depressions occur, and its purpose is to sustain the rails when subjected to extra strain or weight while trains are passing 95 around inclines or curves.

95 The foundation-plate A may be set in and on a prepared foundation, so as to remain firm, or it may be bolted to trestle-work or timbers of bridges by passing bolts through the said timbers and the said plate.

100 It is contemplated to make the rail-rest B in one flexible piece or without a splice-joint and have all the other constructions thereof, substantially as described, remain unchanged, and doing this would be within the scope of 105 my invention; but as by thus making it in one piece the expense and inconvenience would be so greatly increased as compared with making it in two pieces, as shown, I regard the plan shown as far preferable to the 110 modification just proposed.

115 What I claim, and desire to secure by Letters Patent, is—

1. In a metal railroad-tie, in combination, a foundation-plate provided with abutment-ribs in rear of the standards of the rail-rest and a flexible transverse rail-rest having abutment-ribs for the rails between the said standards of the rail-rest, substantially as and for the purpose described.

120 2. In a metal railroad-tie, in combination, the plate A , provided with abutment-ribs $a a^2 a^3$, abutment-blocks a^5 , having beveled portions c^5 and lugs c^8 , and a flexible rail-rest B , having foot portions c^2 , with beveled portions c^4 and a notch c^9 , substantially as and for the purpose described.

125 3. In a metal railroad-tie, the flexible rail-rest B , formed with foot portions c^2 , curved standard portions f , and abutments $m m'$ inside of or between the standards, substantially as described.

130 4. In a metal railroad-tie, in combination, the flexible rail-rest B , having abutments m

m' between its standards, chair-plates C C', and the foundation-plate A, having abutments for the feet of the rail-rest, substantially as described.

5 5. In a metal railroad-tie, in combination, the flexible rail-rest B, chair-plates C C', extended beyond the edges of the rail-rest, and gripping-clips D, passed under the rest and through the chair-plates, substantially as described.

10 6. In a metal railroad-tie, in combination, the rest formed of two spliced parts c c', provided with abutment-ribs $m' m'$, and having parallel portions terminated in shoulders h' , then tapered for a portion of their length, then made of uniform thickness from said tapered portion to their standards f, then bent into curved standards of a thickness equal to the last-mentioned portion, and terminating in thicker abutting foot portions, substantially as and for the purpose described.

15 7. In a metal railroad-tie, in combination, the flexible rail-rest having abutment-ribs between its standards and provided with standards and abutting foot portions, said portions extending inward from said standards a greater distance than outward, substantially as and for the purpose described.

20 8. The flexible spliced rail-rest, in combination with a rigid foundation abutment-plate, substantially as described.

9. The abutment-ribs a of the foundation-plate A, made of less height than the abutment-ribs a' and with a bevel surface a^4 , substantially as and for the purpose described. 35

10. The abutment-ribs $m' m'$ of the rail-rest, those m' being made of a less height than the ribs m , in combination with the differently-formed chair-plates C C' and the rails C² C³, substantially as and for the purpose described. 40

11. The combination of the auxiliary braces E, rail-rest, rail, and foundation-plate A, substantially as and for the purpose described.

12. In combination with a rigid or solid plate or foundation, a flexible transverse rail-rest receiving the rail between its bearings, said transverse rail-rest yielding at once, under a load, bodily throughout its entire length and thickness between the foundation-supports, and in thus yielding assuming a downwardly-curved or approximately-segmental form, and when the load is withdrawn resuming its original straight shape, substantially as described. 45 50

In testimony whereof I hereunto affix my 55 signature in presence of two witnesses.

BENJAMIN W. ELLICOTT.
